CLAIM

The ornamental design for a sand play board, substantially as shown and described.

DESCRIPTION

FIG. 1 is a top perspective view of a sand play board, showing my design.

FIG. 2 is a front view of the sand play board of FIG. 1.

FIG. 3 is a back view of the sand play board of FIG. 1.

FIG. 4 is a left side view of the sand play board of FIG. 1.

FIG. 5 is a right side view of the sand play board of FIG. 1.

FIG. 6 is a top view of the sand play board of FIG. 1; and,

FIG. 7 is a bottom view of the sand play board of FIG. 1. The broken lines illustrate environmental features that form no part of the claimed design.

1 Claim, 5 Drawing Sheets(56)
